UNITED STATES PATENT OFFICE.

JOHN JANICKI, OF CHICAGO, ILLINOIS, ASSIGNOR TO WESTERN ELECTRIC COMPANY, INCORPORATED, OF NEW YORK, N. Y., A CORPORATION OF NEW YORK.

APPARATUS FOR COVERING CORES.

1,378,961.

Specification of Letters Patent.

Patented May 24, 1921.

Application filed December 26, 1917. Serial No. 208,837.

To all whom it may concern:

Be it known that I, JOHN JANICKI, a citizen of the United States, residing at Chicago, in the county of Cook and State of

5 Illinois, have invented certain new and useful Improvements in Apparatus for Covering Cores, of which the following is a full, clear, concise, and exact description.

This invention relates to an apparatus for 10 covering cores, and more particularly to an apparatus for applying a covering of tape to wire, thread, or any other type of cores.

One of the principal difficulties encountered, in the operation of covering cores, 15 such as wire, with tape, resides in the lack of control of the tape serving mechanism, especially so when fragile tapes such as paper are used. This lack of control results in the application of varying degrees of tension on the tape which causes frequent interruptions because of the tearing of the tape during the operation of serving it to the core.

One of the objects of this invention, therefore, 20 consists in the production of an improved apparatus for applying covering tape to cores, in which the tape serving mechanism can be absolutely controlled and in which the tape is laid on the core by a combined wrapping and troughing action.

Another object comprises the production 25 of an improved apparatus in which the tape is subjected to a uniform tension as it is applied to the core and whereby the tape will not be subjected to excessive tensions by 30 rapid accelerations inherent in the commercial operation of substantially all apparatus of this type.

A further object consists in the production 35 of an improved apparatus in which the amount of tension to which the tape is subjected may be readily adjusted and controlled.

Other features reside in the production of 40 improved tape pad or disk mounting means, tape serving means, core guiding means, and others to be pointed out in the following description and the appended claims.

The invention is illustrated in the accompanying drawings, in which:

Figure 1 illustrates a front elevation of the complete apparatus;

Fig. 2 is a front elevation of the wire serving pedestal;

Fig. 3 is a plan view partly in section of 55 the rotating flier;

Fig. 4 is a front elevation thereof;

Fig. 5 is an enlarged fragmentary front elevation illustrating the tape tension controlling means;

Fig. 6 is an end view partly in section of 60 the operating and adjusting devices of the retarding mechanism taken on the plane 6-6 of Fig. 5 and shows its relation to the brake sleeve and its coöperating disk, 65 which have been shown outside of said plane;

Fig. 7 is an end view of the flier and illustrates the tape and wire guiding and controlling mechanism;

Fig. 8 is an enlarged perspective showing 70 the method of feeding the tape to the wire, and

Fig. 9 is an enlarged sectional view illustrating the wire tensioning device.

The specific embodiment of the invention herein illustrated and described comprises a machine used for covering wire with paper ribbon or tape for insulating purposes. Wires thus covered are used extensively as 80 conductors in telephone cables, and the like. Various different grades of paper may be used for such an insulating covering, which papers vary considerably in their tensile strength, and consequently means must be 85 provided in a machine of this type whereby the tension on the paper may be regulated and positively controlled. The tensile strength of paper also varies very perceptibly with atmospheric conditions, humidity 90 tending to materially decrease the strength thereof. If the efficiency of the operation of insulating wire with a covering of tape is to be maintained at its maximum, it is essential, therefore, to avoid tearing thereof. 95

Consequently after the permissible tensile strength, to which a certain grade of paper may be subjected, has been definitely determined, it should be maintained constant irrespective of other varying conditions in the 100

operation of the machine. This result among others is readily obtained by the machine herein described. Obviously, however, the invention is not limited to this preferred embodiment thereof, but is adaptable to many variations and applications without departing from its spirit and scope, as set forth in the appended claims.

As illustrated in Fig. 1, the apparatus 10 consists of a machine base 10, on which are mounted the wire feeding and tensioning mechanism 11, the rotating flier and tape controlling mechanism 12, the capstan 13, and the take-up reel 14. The wire 15 which 15 is to be covered is fed from a coil 16 placed on the wire feeding pedestal 17, the center line of which in the operation of the machine is located directly beneath the end of wire 15 depending from the feeding and 20 tensioning device 11 of Fig. 1. The coil and its associated pedestal have been moved to the right in the drawing to economize space. The wire is fed from the coil 16 over the 25 tensioning disks 21, after which it is given another turn about the sheave 20, and is then fed through the funnel shaped wire guide 22 to the wire guiding means situated in the rotary flier. 30 The wire tensioning mechanism 21 is illustrated in detail in Fig. 9 and comprises a shaft 24 mounted in the bearings 25. A sheave 26 is rigidly secured to said shaft between the loosely mounted sleeves 27 and 35 28. Rigidly secured to the sleeve 28 is the bell shaped disk 29. A like disk 30 is rigidly secured to the sleeve 27, the disk 30 being forced against the disk 29 under the compressive force of the spiral spring 31 in- 40 closing the sleeve 27. The wire 15 as it is fed to the machine must pass from the sheave 26 between the contacting surfaces of the disks 29 and 30, and this will place a tension upon said wire, depending upon 45 the compressive force of the spring 31.

The funnel shaped wire guide 22 functions to aid the operator in directing the wire through the opening 33 in the end bearing of the rotating flier. After the wire 50 has passed through this opening 33 it is carried over a sheave or pulley 34 rotatably mounted on said rotating flier, said sheave having its outer peripheral wire guiding surface substantially in the axis of rotation 55 of the rotary flier. From this sheave 34 the wire is guided to the sheaves 35 and 36 which are rotatably mounted on one of the lateral arms 38 of the flier. These sheaves 35 and 36 are located outside the axis of 60 rotation of the flier and serve to guide the wire around the paper pad mounting and serving mechanism hereinafter to be described. The wire after leaving the sheave 36 is directed to a rotatable sheave 37 the

outer peripheral wire guiding surface of 65 which is substantially in the axis of rotation of the rotating flier, and from this sheave the wire is threaded through a central perforation in a conical shaped projecting lug 39 secured to the right end bearing 70 of the rotatable flier. (See Figs. 5 and 8.)

The flier comprises the lateral arms 38 and 40 which are rigidly secured at either end to the rotatable shafts 41 and 42, both 75 of which are suitably journaled in bearings such as 43, each of which is equipped with a ball race 44 and balls 45, whereby the frictional resistance of the rotating elements of the flier will be reduced to a minimum. Centrally mounted in the lateral arms 38 and 40 of the flier are the rotatable hollow shafts 46 and 47 respectively, the axes of which are in alinement and at right angles to the axis of rotation of said flier. 80 The shaft 46 is rotatably mounted in the lateral arm 38, said mounting comprising the ball bearings 53, 54, 55, and 56; and the shaft 47 is rotatably mounted in the lateral arm 40, said mounting comprising 90 the ball bearings 57 and 58. A cylindrical tube 60 is slidably mounted in the shaft 46, and a cylindrical tube 61 is slidably mounted in the shaft 47. A cylindrical rod 48 is slidably fitted in the tube 61. The inner end of the tube 60 is tapped to engage the threaded inner end of the rod 48 whereby said tube and rod may be connected in threaded engagement at 62, as illustrated in Fig. 3.

The shaft 46 carries a light dish shaped disk 63 rigidly secured thereto. This dished disk 63 is provided with a stiffening plate 64 which serves to strengthen said disk and prevent distortion or displacement 100 thereof when it is subjected to the high speed of rotation of the flier. Without this plate the disk might be distorted, due to the excessive gyroscopic action generated, and thus throw the rotating elements of the 105 flier out of balance. The shaft 47 carries a disk or spider 65, the weight of which is substantially equal to that of the disk 63, said shaft 47 being slidably fitted between the tube 61 and the ball bearings 57 and 58. The rod 48 carries the hand nut 66 whereby 110 said rod may be rotated out of threaded engagement with the threaded end of the tube 60. When the threaded end of the rod 48 has been completely removed from the threaded portion of the tube 60, the rod 48 may be drawn forward. In this movement the rod is drawn into the tube 61 until the threaded end thereof is flush with the end of the tube, at which time the enlarged threaded portion 115 of said rod engages the shoulder 49 in said tube. Further movement of the rod will carry with it the sleeve 61, due to the abut- 120

105

110

115

120

125

ting surfaces of said rod and shoulder. The rod and sleeve will then move together until the enlarged circular disk 51 on the end thereof is completely inclosed in a recess 52 fitted in the disk 65, at which time the ends of the rod 48 and the sleeve 61 and the inner face of the disk 65 will all be flush. Further movement of the rod 48 will now carry with it the shaft 47 and the disk 65, due to the abutting surfaces of the disk 51 and the recess 52, and this movement may be continued until the hub 67 of the disk 65 has been completely drawn into the recess 68 situated in the lateral arm 40 of the flier:

15 When the rod 48, the tube 61, the shaft 47, and the disk 65 have been thus withdrawn, a large opening intervenes between the opposing faces of the disks 63 and 65, and consequently in this position of the disks it is 20 possible to interpose therebetween a disk of insulating tape or paper, such as 70. Disks of insulating paper such as 70 are ordinarily provided with a central aperture 71 for mounting purposes. This central aperture 25 71 is preferably fitted over a series of projecting fingers such as 72 and 73 which are circumferentially arranged about the end of the shaft 46. Normally when the rod 48 is not in threaded engagement with the tube 30 60, the circumferential fingers 72 all rest in substantially the same position as that shown for the fingers 73. The fingers 72 serve as a clamping means for holding the disk 70 in position, but obviously any suitable means 35 may be utilized for this purpose. In the preferred embodiment illustrated in Fig. 3 the fingers are pivoted at 74 and a finger such as 72 is pivotally interposed between two projecting fingers 73, which are integral with the shaft 46, all the way around the circumference of the disk.

When the paper disk 70 has been placed in position so that the apertures 71 incloses the series of fingers 72 and 73, the threaded 45 portion of the tube 60 and the rod 48 are brought into engagement and screwed up tight by means of the hand nut 66. When the hand nut 66 has been drawn up tight, the pad of paper 70 is rigidly held between 50 the disks 63 and 65 and said pad 70 is firmly held and is in addition positively positioned by means of the pivoted fingers 72. Thus during the last few turns of the rod 48 the disk 65 is held against movement by the disk 55 63 and the interposed pad 70, and at this time the tube 60 is moved forward. In this movement the inwardly projecting pins 75 of the fingers 72 will be moved forward by a grooved flange 77 integral with the tube 60, and said pins will rotate these fingers about 60 their pivots 74 which in turn will cause the forward protruding ends of the fingers 72 to securely engage the outer surface of the aperture 71 in the pad 70. The screwing up

of the hand nut 66 will consequently position 65 the pad 70 centrally with respect to the axis of rotation of the rotating disks 63 and 65, will securely clamp said paper pad between these disks, and will interconnect the two disks by means of the rod 48 and the sleeve 70 60. When the paper pad is thus mounted between the disks it is free to rotate with the disks which rotate about their ball bearing mountings hereinbefore described.

When the paper disk core is to be removed 75 from the machine the first few turns of the hand nut 66 will release the fingers 72 and they will be retracted to their normal position—that is, the position always maintained by the fingers 73, due to the action of a 80 spiral spring 80. The spring 80 is maintained under compression between an end flange on the sleeve 60 and the bearing housing and consequently tends to draw the grooved flange 77 inclosing the pins 75 85 against the end face of the shaft 46. Said spring will consequently function to withdraw the sleeve 60 and rotate said fingers about their pivots 74 to their normal position.

When the disk is positioned and mounted between the disks 63 and 65 it will be so situated in the rotatable flier that one of its median diameters will be substantially in alignment with the axis of rotation of said 95 flier, the axis of rotation of the pad of paper 70 for the purpose of unrolling said paper being at right angles to the axis of rotation of the flier. When the pad of paper 70 has been thus mounted in the flier the paper can 100 be unrolled therefrom and guided about proper paper guiding mechanism to the position from which it is served to the wire.

The paper after leaving the pad is guided around the two rollers 81 and 82 of the 105 tumbler roller mechanism 83, (see Fig. 5) and from there it is guided over the lower surface of a spoon shaped projecting finger 84 from where it passes through an opening in the right-hand bearing of the flier, 110 through which opening it is fed to the wire. The tumbler mechanism 83 is mounted with its pivoted center in the axis of rotation of the flier, and the length of the lever arms from said center to the mounting center of 115 either roller 81 or 82 is maintained as short as possible to avoid to the greatest permissible extent the action of the centrifugal force, due to the rotation of the flier, on the operation of said tumbler mechanism. The 120 tumbler mechanism 83 comprises arms 76 which carry the rollers 81 and 82. The arms 76 are rigidly secured to a rotatable shaft on which is also secured a plate 85 equipped with a nose 86 which engages a projecting plate 87 rigidly secured to a brake shoe 88 which rides on the inner surface of the upturned portion 89 of the dish shaped disk 63.

This brake shoe 88 is held in frictional contact with the upturned surface 89 of the disk 63 by means of a spiral spring 90 secured to a rotatable pin 91 which carries the 5 arms 92 and 93 integral with the brake shoe 88. (See Fig. 6.) The spring 90 has a projecting end 94 which is arranged to be fitted into circumferential slots such as 95 in the semi-circular shaped plate 96 secured to the 10 lateral arm 38 of the flier. When the projecting portion 94 of the spring 90 is rotated in a clockwise direction and inserted in any of the slots 95 traversed in turning the protruding portion 94 in this direction, the force 15 stored in the spring 90 is increased and the frictional contact between the brake shoe 88 and the surface 89 of the disk 63 is likewise increased. This mechanism consequently 20 serves as a means for determining the amount of frictional contact which shall exist between the brake shoe and the surface 89 and consequently likewise determines the retarding force which shall be exerted against the rotation of the disks 63 and 65 and the 25 inclosing disk of paper 70. This retarding force can consequently be readily adjusted for various grades of paper, the amount thereof depending upon the tensile strength of the paper which is to be employed.

30 The amount of this retarding force having been determined, it is essential that it be maintained constant. However, it will be evident that the tension required to unwind the paper from the disk 70 will vary between 35 a large disk and a very small disk, the amount of force required to unwrap the disk being proportional to the length of radius of said disk, which radius constitutes the lever arm through which the force is exerted 40 by which the paper is unwound from said disk. Consequently as the paper is unwound, the amount of force required to unwrap the paper from the disk will gradually increase. In order that the tension on 45 the paper be maintained constant, it is necessary, therefore, that the retarding force exerted on the paper holding disk be gradually decreased in an amount equal to the increase due to the reduction in the size of 50 the paper pad. This is accomplished by the tumbler roller mechanism 83.

It will be evident that as the force required to unroll the paper from the pad increases, the force exerted tangential to the lower periphery of the tumbler roller 81 will increase, which action will likewise be true of the upper portion of the tumbler roller 82, and consequently the tumbler roller mechanism 83 will be given a very slight rotation 55 in a clockwise direction, depending upon the increase of said tension. The nose 86 of the plate 85 will therefore ride against the protruding plate 87 which will push back the brake shoe 88 against the action of the spring

90, thereby decreasing very slightly the frictional contact between the shoe and the surface 89, said reduction being equal in amount to the very slight increased tension exerted on the paper in removing it from the pad 70. The tumbler roller mechanism thus automatically reduces the frictional retarding action as soon as the tension on the paper tends to increase and thereby serves as an automatic means for maintaining a uniform tension on the paper. Therefore when the 75 amount of tension to which the paper can be safely subjected has been determined and the amount of said tension has been set by means of the spring 90 and its associated mechanism, this tension will be automatically maintained by the action of the tumbler mechanism 83.

After the paper leaves the tumbler roller mechanism, it is fed under the spoon shaped projecting lug 84. This lug is fitted with a 85 convex paper contacting surface whereby the paper is given a troughed form just prior to the time that it is laid on the wire. (See Figs. 8 and 5). The spoon 84 is arranged for vertical adjustment by means of 90 the screws 100 and 101, whereby the angle at which the paper is fed to the wire from the troughed or spoon shaped piece 84 can be readily determined. Naturally the lower the spoon 84 is placed, the sharper will be 95 the angle of application, and vice versa. The angle at which the paper should be applied to the wire depends upon the tensile strength of the paper which is being used. The stronger the paper, the sharper will be 100 the angle at which it may be applied.

The apparatus may be driven from any suitable source, and for convenience in the drawing the driving means has been illustrated by the belt 103. This belt drives the 105 pulley which rotates the flier. This driving pulley is fitted with a groove which carries a second belt 104, which through a suitable reduction drives the belt 105 which in turn drives the capstan 13. This amount of reduction—that is, the relation of the rotation per minute of the flier as compared to the rotations per minute of the capstan, will determine the number of layers of paper applied to the wire per linear foot thereof.

In the operation of the machine, the wire is first strung from the coil 16 through the capstan 20 and the tensioning mechanism 21, and is then fed over the wire guiding sheaves of the flier and thence through the 120 conical piece 39 and through a sleeve 110 secured to a projecting arm 111 adjustably fastened to a rod 112 projecting from the frame of the machine, to the capstan 13. The wire is then given several turns about 125 the capstan 13, after which it is fed to the supply reel 14 which is driven by any suitable means, as for example, the belt 113.

After the wire has been thus strung through the machine the paper disk 70 is properly positioned and clamped between the holding disks 63 and 65. The paper is then unrolled 5 and guided over the tumbler rollers 81 and 82 and the troughing piece or spoon 84, after which it is given several turns about the wire. The machine is now started and the wire will be advanced therethrough by the 10 rotation of the capstan, the wire drawing with it the paper tape which will be unrolled from the disk 70. As the paper is withdrawn from the disk 70 it is likewise rotated, due to the rotation of the flier, and 15 this rotation of the flier together with the paper serving and forming piece 84 will serve to lay the paper on the wire in smooth even layers as said wire is drawn through the machine. Due to the shaping action of 20 the troughing piece 84, the paper, just prior to its application to the wire, is given a semi-sleeve shape, and the action of applying the paper to the wire consists essentially in applying this semi-sleeve shaped surface 25 to the surface of the wire and then drawing it taut by a wrapping movement due to the rotary action of the flier. After the paper is thus applied to the wire it is drawn through the sleeve 110 which removes any 30 irregularities which may exist in the exterior paper covering.

The apparatus, as herein described, comprises distinct advantages, in that a fresh supply of insulating paper can be readily 35 added to the machine without in any way affecting the wire guiding or drawing mechanisms. The apparatus also acts as a wire straightener, in that the wire is subjected 40 to a straightening action by the guiding sheaves through which it is drawn in feeding it to and from the flier. In this action the wire is subjected to two twists, one on entering the flier and one on leaving the flier, which twists are in opposite directions, 45 and this action serves to straighten the wire before the covering of paper is applied thereto. The tumbler roller mechanism which automatically maintains a uniform tension on the paper is arranged for very 50 great sensitiveness, being mounted centrally—that is, in the axis of rotation of the flier, so as to be removed as much as possible from the detrimental action of the developed centrifugal force due to the rotation 55 of the flier. Since the moving arms of the tumbler are maintained comparatively short and frictional regulation is readily obtained with a very slight movement of the brake shoe 88, the angle through which the tumbler 60 must be displaced from the perpendicular to obtain the desired regulation is exceedingly small. This mechanism is exceedingly sensitive, therefore, at rotary speeds as high as 5000 revolutions per min-

ute, the tumbler mechanism being substantially unaffected by the developed centrifugal force. It will consequently be evident that even at very high speeds the paper ribbon is under absolute mechanical control and the tension thereof can be suitably regulated and maintained. All the rotating parts are designed so as to be in rotary balance, which is essential for the successful operation of the machine. 65

Obviously the invention is not limited to the specific apparatus herein illustrated and described, which constitutes but one of the many physical expressions of this invention, the scope and spirit thereof being set forth in the following claims. 70

What is claimed is:

1. In a mechanism for covering wire with tape, a tape roll, a rotatable flier in which said tape roll is rotatably mounted, a wire to be served with tape from said roll, a pressure controlled brake for said tape roll, a centrally pivoted arm operatively connected with said brake, and pulleys upon the ends of said centrally pivoted arm over which said tape passes in opposite directions to control the application and release of the brake pressure upon said tape roll in accordance with the tension upon said tape. 85

2. In a mechanism for covering wire with tape, a tape roll, a rotatable flier in which said tape is rotatably mounted, a wire to be served with tape from said roll, means for frictionally retarding the movement of the tape roll, a lever centrally pivoted in the axis of rotation of said flier, and means whereby the tape is caused to exert pressure in opposite directions upon the ends of said lever to control said frictional retarding means. 95

3. In a device of the character described, a rotatable flier, stationary wire guiding means situated at each end of said flier and in the axis of rotation thereof, a disk integral with and a disk slidably mounted 100 on shafts at right angles to the axis of rotation of the flier, said disks being operable to clamp a coil of tape therebetween with one of its median diameters substantially in the axis of rotation of said flier, means frictionally engaging said integral disk, a tape guiding means comprising a pair of tumbler rollers, means for advancing said wire whereby said tape is served to said wire to completely inclose the same by the combined 110 action of the revolving flier and the tape guiding means, and means operated by said tumbler rollers which controls the aforesaid frictional engaging means whereby said tape is subjected to a uniform tension 120 as it is withdrawn from said coil irrespective of the size of said coil. 115

4. In a device of the character described,

in combination, a rotatable flier, a tape disk mounting means associated with said flier having an axis of rotation perpendicular to the axis of rotation of said flier, a wire feeding means, wire advancing means for pulling the wire from said feeding means through said flier, means for retarding the rotation of the tape mounting means, a pair of tumbler rollers operated to guide said

tape and control said retarding means, and an adjustable tape guiding means controlling the angle at which said tape is laid on said wire as said wire is advanced and the tape fed thereto from said disk.

In witness whereof, I hereunto subscribe my name this 5th day of December, A. D., 1917.

JOHN JANICKI.
